UNITED STATES PATENT OFFICE.

CHARLES R. KEIL, OF TIFFIN, OHIO, ASSIGNOR TO UNITED STATES GLASS COMPANY, OF PITTSBURGH, PENNSYLVANIA, A CORPORATION OF PENNSYLVANIA.

DESIGN FOR A GOBLET OR SIMILAR ARTICLE.

Application filed February 25, 1928. Serial No. 25,578. Term of patent 14 years.

To all whom it may concern:

Be it known that I, CHARLES R. KEIL, a citizen of the United States, residing at Tiffin, county of Seneca, State of Ohio, have invented a new, original, and ornamental Design for Goblet or Similar Article, of which the following is a specification, reference being had to the accompanying drawing forming a part hereof.

The figure in the drawing is a side eleva-

tion of a goblet, showing my new design. The dominant feature of the design is the stem which is illustrated in solid lines.

I claim:—

The ornamental design for a goblet or similar article, as shown and described.

In testimony whereof I have hereunto set my hand.

CHARLES R. KEIL.
